UNITED STATES PATENT OFFICE.

JOHN O. ROBINSON, OF ALBIA, IOWA.

BURIAL-VAULT.

1,049,269.

Specification of Letters Patent. Patented Dec. 31, 1912.

Application filed October 18, 1911. Serial No. 654,534.

To all whom it may concern:

Be it known that I, JOHN O. ROBINSON, a citizen of the United States, residing at Albia, in the county of Monroe, State of Iowa, have invented certain new and useful Improvements in Burial-Vaults; and I do hereby declare the following to be a full, clear, and exact description of the invention, such as will enable others skilled in the art to which it appertains to make and use the same.

This invention relates to concrete burial vaults and more particularly to the means for sealing the cover, the particular object of the invention being to provide such a specific form and arrangement of the sealing receiving channel as will insure against loosening of the sealing medium in the event of it being cracked vertically into sections.

In the drawing; Figure 1 is a perspective view of a vault constructed in accordance with my invention, the cover being removed therefrom, Fig. 2 is a longitudinal sectional view through such a vault, the cover being shown in its closed position, and Fig. 3 is a cross sectional view taken on the line 3—3 of Fig. 2.

Like reference numerals designate corresponding parts in all the figures of the drawing.

Referring to the drawing, the vault is formed of concrete or any other suitable plastic material, and includes a body which consists of a bottom 5, side walls 6—6 and end walls 7—7. The upper portions of the side and end walls 6 and 7 are preferably thickened as indicated by the reference numerals 6^a and 7^a respectively. The upper inner corners of the portions 6^a and 7^a are rabbeted to respectively form a consequent bottom 8 and a downwardly and outwardly inclined wall 9. Formed in each wall 6 and 7 and communicating with each bottom 8 is a centrally disposed longitudinal groove 10, the distance between said groove and the inner face of a respective wall forming a consequent shoulder 11.

My invention further comprises a top 12 which is likewise formed of cement or other plastic composition. This top is of a size to rest upon the shoulders 11, and has its side walls 13 downwardly and outwardly inclined to correspond to the inclination of the inclined walls 9. These walls 13 preferably extend to the inner wall of the groove 10.

The cover 12 is positioned upon the shoulders 11 as above noted. Cement 14 is then poured into the space between the walls 13 of the cover and the inclined walls 9 of the body and also into the grooves 10. When this cement or other sealing material becomes hardened, it will be impossible to remove the cover 12 without first removing the cement 14, because of the fact that the walls 13 of the cover and the walls 9 of the body are inclined and thereby cause the body of cement 14 to project over the lower edges of said cover. By reason of the cement being disposed within the groove 10, any moisture will be prevented from working around and into the interior of the vault.

Referring particularly to Fig. 2 of the drawings, it will be noted that after the lid is in place and the grouting is poured in, that the grouting assumes such a peculiar shape as that even if the grouting after drying is broken vertically into sections, it cannot be withdrawn or cannot fall out in the event the vault is turned on its side. This is because the bed which fills the groove 10 extends vertically downwardly while the portion 14 of the seal extends at an obtuse angle thereto. In consequence, any upward and lateral movement of the portion 14 draws the lower bed outwardly against the side wall of the groove 10, thereby being formed an efficient lock.

What is claimed is:

In a burial vault, the combination with a body having a rabbet formed in the inner portion of its upper edge, said rabbet including a horizontal bottom wall having a vertically extending rectangular groove

longitudinally thereof and spaced from the longitudinal edges of the wall, the other wall of the rabbet overhanging in part the groove, a lid disposed upon the bottom of the rabbet flush with the inner edge of the groove of the latter, the side wall of the lid extending upwardly and parallel with the overhanging wall of the rabbet, and a

sealing material cast into the space between said walls and into the groove. 10

In testimony whereof, I affix my signature, in presence of two witnesses.

JOHN O. ROBINSON.
